UNITED STATES PATENT OFFICE.

CHARLES A. REINERS, OF HOBOKEN, NEW JERSEY, ASSIGNOR TO ELEVATOR SUPPLY & REPAIR COMPANY, A CORPORATION OF ILLINOIS.

ELEVATOR SIGNALING APPARATUS.

No. 864,915.

Specification of Letters Patent.

Patented Sept. 3, 1907.

Application filed April 9, 1907. Serial No. 367,140.

To all whom it may concern:

Be it known that I, CHARLES A. REINERS, a citizen of the United States, residing at Hoboken, New Jersey, have invented certain new and useful Improvements 5 in Elevator Signaling Apparatus, of which the following is a clear, full, and exact description.

My invention relates to an elevator signaling apparatus, and my object is to provide a construction by 10 which an attendant, commonly called the "starter", may control the movement of the elevator cars in order to cause them to make their trips with regularity.

In tall buildings provided with a large number of elevators it is usual to have an attendant at the "starting floor", usually the ground floor, to direct the starting 15 of the cars and to, so far as possible, keep them running regularly, so as to give the greatest possible service. It often happens that a car will be despatched by the starter from the lower floor at the proper time, but, on account of an unusual number of stops, said car 20 may be unusually delayed and a succeeding car may overtake it, in which case both cars might simultaneously arrive at the starting floor again, and it is desirable in such cases to be able to cause the first departing car to hasten down, if the starter finds, from looking 25 at the indicators, which are usually provided at the starting floor, that one car is being so delayed. The Smalley & Reiners patent No. 634,220 dated October 3, 1899, and the Pedersen patent No. 629,302 July 18, 1899, disclose constructions in which also-called "trans- 30 fer button" in each car is provided by which the operator of a car may pass floors where intending passengers have pushed their buttons and still leave the circuits in condition to cause the next car to be signaled which is moving in the same direction. It will be ob- 35 vious, however, that such constructions are not under the control of the starter, and the elevator operator may not know that he is being delayed. The Collett patent 700,619 May 20, 1902 discloses a construction by which 40 the starter may signal to the operator to come down without a stop, but in the use of such device it has been found that the operators do not, in many cases, obey such signal. In the embodiment of my invention shown in the drawings there is provided a "starter's controller" for each car operable from the starting floor 45 by the starter so as to prevent the operator of the car from receiving signals to stop which would otherwise be transmitted to him, and which will, at the same time, leave the circuits for the other cars in such condition that they may be signaled to stop.

50 My invention will be set forth in the claims.

In the drawing, Figure 1 represents diagrammatically an embodiment of my invention applied to two cars and shafts for only the downward movement of the car; and Fig. 2 represents the parts of two commutators

for one floor and the connections for both directions of movement.

In the embodiment of my invention shown in Fig. 1, I have illustrated two cars, 1 and 2, which are supposed to be moving up and down in their respective shafts, and I have provided visual signaling means, preferably electrically operated, for each shaft in order to signal the operator to stop at the different floors. Such signaling means may be embodied in different forms, but I prefer to have a single signal carried by each car, and in the present embodiment I have provided electric 60 lamps 3 and 4, one for each car. As a means for operating such signals to indicate to the operator at which of the intermediate floors (4th, 5th and 6th in the drawings) to stop, I have provided a "passenger's controller" for each of said floors which are operable from each 70 of such floors and which are adapted to control the car signals. I have called this a "passenger's controller" because it is operated by a passenger who intends to signal a car to stop for him. Such a "passenger's controller" is indicated, for example, by the switch arm 9 75 and its mercury pot 10. Such switch is operable from the floor to which it corresponds by, for example, a push button, such as 6 on the 5th floor, which, when closed, energizes the "setting" magnet 11, draws back the retaining detent 12 and allows the switch arm 9 to 80 fall into the mercury pot. I do not consider it necessary to describe this more in detail, as the same is well known in the art and is fully described and illustrated in the Smalley & Reiners patent before mentioned. I prefer this construction of "passenger controller", 85 but it will be obvious that other constructions may be provided, if desired. Corresponding to each of the other floors is a similar switch, the one for the fourth floor being indicated at 13, 14, and its setting magnet at 15, and for the sixth floor at 17 to 20. Such switches 90 are preferably placed somewhere on the overhead, but may obviously be placed at any desired point.

I prefer that the "passenger's controller" shall not, by itself alone, determine the time when the signal shall be given, and in the present embodiment I have provided means which prevents the signal from being given except when a car is approaching the floor on which one of the push buttons has been pushed, and I have illustrated parts of an embodiment of commutator for each floor, such commutator consisting, in the present embodiment, of fixed and moving contact plates or terminals, the moving portions of the commutator being moved correspondingly to the movement of the car as is common in the art. Fig. 1 shows the contacts and brushes for three floors used in the downward movement of the cars, the "up" contacts and brushes being omitted. The portions of such two commutators are indicated at the upper corners of Fig. 100 105

1, the one at the left upper corner comprising long contact plates 21 and 22, several short contact plates indicated by 23 to 33, which are all fixed, and the moving contact brushes 47 to 52. The commutator at the right comprises fixed contact plates 34 to 46, and moving brushes 53 to 58.

The elevators are in Fig. 1 considered to be moving downwardly and the moving brushes of the commutator traveling in the direction shown by the arrows, and 10 only so much of such commutators and wiring has been shown as is used in the downward movement of the car, and I have not thought it necessary in this figure to completely illustrate the wiring and construction of commutator for the opposite direction of movement 15 of the car, as the same will be evident to one skilled in the art from the Smalley & Reiners patent, before mentioned, or their Patent 826,752.

It will be obvious that, if the push button 6 on the fifth floor has been pushed, it will energize magnet 11 20 and drop the switch arm 9 into the mercury pot 10, and as soon as moving brush 50 of the commutator has reached the point shown where it contacts with plate 24, a circuit will be closed through the lamp 3 in the car 1, and the parts are preferably so proportioned that 25 the operator will receive the signal when the car is a floor and a half or two floors away from the floor at which he is to stop. I have also provided visual signals for 30 signaling the intending passengers on the floors that a car is approaching, and in the drawings, 59, 60 and 61 indicate so-called "floor lamps" located outside the shaft in which car No. 1 is moving, and other floor lamps 62, 63 and 64 located outside the shaft in which car No. 2 is moving, as is common in the art and more 35 fully explained in said Smalley & Reiners patents. It will be obvious that after the push button 6 has been 40 pushed the floor lamp 60 will be lighted up when the moving brushes 51 and 52 contact with the plates 24 and 27, respectively, and it is usual to so arrange the parts that the floor lamp will be lighted up a short time in advance of the car lamp.

In order to restore the signal circuits to normal condition after the passenger has been taken aboard the car, I have provided devices corresponding to each floor for 45 restoring the signal circuits of both cars to normal condition, and I preferably accomplish this by providing the commutators with fixed plates 29 to 31 and 36 to 38, which obviously correspond with each of the three intermediate floors. When the moving brush 48 strikes contact 30, for example, it will cause the "restoring 50 magnet" 66 corresponding to that floor to be energized, which will raise the pivoted lever 9 out of the mercury pot and allow the weighted detent 12 to engage the same and hold it out of the pot. It will be obvious that such 55 restoring magnets and "set back" contacts correspond to each of the floors. I do not consider it necessary to explain this construction more in detail, as it is well known in the art and is more fully described in said Smalley & Reiners patent. It will be obvious that when any restoring magnet is energized, it will break 60 the circuit at its mercury pot leading to both the floor lamps of that floor and the car lamps, and restore such circuits to normal condition.

68 and 69 are so-called "transfer buttons" in the cars by which the operator of the car may pass a floor without 65 restoring the circuits of that floor to normal condi-

tion, as is well known in the art and is more fully described in said Smalley & Reiners patent 634,220. The parts of the commutator at the left are represented as being in the position they would be when car 1 is at about the seventh floor, and the moving brushes of the 70 commutator at the right are in the position they would be when the car 2 is, for example, at the tenth floor. If the car 2 had been delayed and it were desired to hurry it down so as to arrive at the starting floor before car No. 1, it would be desirable to enable the starter to prevent 75 the operator of car 2 from receiving the signals for a certain distance of travel of the car, preferably until he reaches the starting floor again, and in order to do this I have provided what I have termed a "starter's controller" for each car which is operable from the starting 80 floor and either of which, when operated, makes the signaling means of only its shaft inoperative for a certain distance of travel, in this case until the car reaches the starting floor. In the present instance I have provided 85 a normally-closed switch in the car light circuit of each car which is operable from the starting floor. Such switch is indicated for the car at the right by the mercury pots 70, 71, and U-shaped bridge 72, carried on the pivoted arm 73. This is controlled, in the present instance, by a normally-open push-button 74 on the 90 starting floor, which, when closed, energizes a magnet 75 which will move the lever 73 from the position shown at the left of the drawing to that shown at the right of the drawing, thus raising the bridge 72 out of the mercury 95 pots, breaking the circuit at that point and allowing the weighted detent 76 to hold it in its raised position. The restoring circuits may also be broken at the same time at the mercury pots 77 and 78, if desired.

I prefer to restore the switch arm 73 to normal closed condition by means of a device which will automatically act, or only be operable, when the car reaches or is at a certain point in the shaft, preferably about the starting floor, and I prefer to accomplish this by means of a part which is moved correspondingly with the car. In the present embodiment I have provided two extra 105 fixed contact plates 32 and 33 for the car at the left, and 39 and 40 for the car at the right, and it will be obvious that, in the case of the car at the right, when the moving brushes 53, 54 reach the contacts 39 and 40, a circuit will be closed through the magnet 79, which will attract its armature 76 and allow the switch arm 73 to again close the circuits at the mercury pots 70, 71, 77, 78, thus restoring the circuits to normal condition.

The starter, having desired to hurry car 2 down, has pushed his button 74 and caused the switch arm 73 to 110 break the circuits, and it will be obvious that thereafter neither the car lamp 4 nor the floor lamps 62 to 64 will be lighted, even though the floor push buttons 5 to 7 were operated, and yet the circuits for the shaft and car at the left will remain in condition to operate the 115 car lamp and floor lights for car 1. As the operator of car 2 will not receive any signal, he will therefore not know that any passenger is waiting for him, and will come on through without stopping, and when the plates 39 and 40 are bridged by the moving brushes 53 and 54, the "starter's controller" will be restored to its normal 120 closed condition.

It will be obvious that the car at the left is also provided with a similar "starter's controller", push-button, and means for restoring the same to normal condi- 130

tion, and that the starter therefore has the signals of both cars under his control and can make the signal of either car inoperative to give its signal to the operator, while at the same time leaving the rest of the system in 5 condition to carry out the normal operations of the apparatus.

While in Fig. 1 and the foregoing description I have not considered it necessary to explain even diagrammatically the construction of the commutator and the 10 wiring for operating the signals in the opposite direction, I do not consider that this is necessary as I consider that a mechanic skilled in this art would, from the foregoing disclosure, clearly understand my invention and would be able to embody it in practical form, particularly 15 if he were familiar with the disclosures of the Smalley & Reiners patent mentioned.

In Fig. 2 I have, to aid in the disclosure of the embodiment of the invention shown in Fig. 1, illustrated two cars and the contact plates of two commutators for 20 only a single intermediate floor (for example, the fifth floor of Fig. 1), and have, in order not to complicate the diagram, omitted therefrom the floor lights and contacts (which may be dispensed with if desired), the push-button mechanism operated by the intending 25 passengers, and the mechanism for energizing the magnets to restore the starter's controller to normal position. The contact plates 21, 22, 24 and 30 are the contacts for actuating the car light and restoring magnet for that floor when the car is moving down, the moving 30 brushes 47 to 50 bridging said contacts when the car is moving down, and the contacts 90 to 93 are the similar contacts for that floor and car when the car is moving up, the moving brushes which contact therewith being indicated at 94 to 97, as explained in the Smalley & 35 Reiners patent 826,752. For example, when the car is moving down, the brushes 47 to 50 bridge the contacts, and the brushes 94 to 97 have been moved to their inoperative position, that is, 94 and 95 both rest on the strip 91, and brushes 96 and 97 both rest on strip 93, 40 thus making the latter set of brushes 94 to 97 inoperative when the car is moving down, and vice versa when the car is moving up. The sections of the commutator at the right for car 2 for that floor are similarly illustrated, together with their brushes, and the brushes of 45 both cars are indicated as in the position they would be when the car is, for example, at the tenth floor and moving downwardly. The commutators in both figures have been illustrated as they may be embodied in a 50 commutator, such for example as illustrated in said Smalley & Reiners patent 826,752, July 24, 1906, but obviously other forms of commutator may be used.

115 and 116 are buzzers in the cars.

It will be observed that the starter's controller when operated, as indicated at the right in Fig. 1, will prevent 55 the operation of the restoring means of the shaft at the right in the sense that it will prevent the restoring brush 54 from completing the circuit through the restoring magnet 66, and that it will also prevent the operation of the floor lights 62 to 64. The car at the right 60 may therefore come on down as an "express" and without lighting up the floor lights or restoring the circuits to normal condition, but will leave the circuits in condition so that the car at the left will go through its normal operation.

65 While I have, in the foregoing, illustrated and de-

scribed one embodiment of my invention, I am fully aware that it may be embodied in widely different forms, and I therefore do not limit myself to the construction heretofore illustrated and particularly described.

70

What I claim is:

1. In an elevator signaling apparatus in combination, two elevator cars and shafts, each shaft having visual signaling means for signaling to the operator of the car of that shaft, means for operating the same to indicate to said operator at which of several intermediate floors to stop and comprising a "passenger's controller" operable from each of said floors and, when operated from any such floor, adapted to cause the operators of both cars to be signaled to stop at that floor, devices corresponding to each of said floors for restoring said signaling means of both cars to normal condition, and a "starter's controller" for each car which is operable from the "starting floor" and either of which, when operated, makes the signaling means of only its shaft inoperative for a certain distance of travel. 85

2. In an elevator signaling apparatus in combination, two elevator cars and shafts, each shaft having visual signaling means for signaling to the operator of the car of that shaft, means for operating the same to indicate to said operator at which of several intermediate floors to stop and comprising a "passenger's controller" operable from each of said floors and, when operated from any such floor, adapted to cause the operators of both cars to be signaled to stop at that floor, and also comprising a part for each car moved correspondingly to the movement of its car and adapted to prevent a signal for any such floor being given except when a car is approaching that floor, devices corresponding to each of said floors for restoring said signaling means of both cars to normal condition, and a "starter's controller" for each car which is operable from the "starting floor" and either of which, when operated, makes the signaling means of only its shaft inoperative for a certain distance of travel. 95

3. In an elevator signaling apparatus in combination, two elevator cars and shafts, an electrically operated visual signal carried by each car, a "passenger's controller" for each of several intermediate floors and each of which is operable from one of said floors and adapted to control the signals of both cars, a part for each car moved correspondingly to the movement of its car and causing the signal of that car to be operative only when one of said controllers has been operated and that car is approaching the floor from which said controller has been operated, devices for each car corresponding to each of said floors for restoring the signals of both cars to normal condition, and a "starter's controller" for each car operable from the "starting" floor and either of which, when operated, makes the signal of only its car inoperative. 105

4. In an elevator signaling apparatus in combination, two elevator cars and shafts, an electrically operated visual signal carried by each car, a "passenger's controller" for each of several intermediate floors and each of which is operable from one of said floors and adapted to control the signals of both cars, a part for each car moved correspondingly to the movement of its car and causing the signal of that car to be operative only when one of said controllers has been operated and that car is approaching the floor from which said controller has been operated, devices for each car corresponding to each of said floors for restoring the signals of both cars to normal condition, and a "starter's controller" for each car operable from the "starting" floor and either of which, when operated, makes the signal of only its car inoperative. 110

5. In an elevator signaling apparatus in combination, two elevator cars and shafts, an electrically operated visual signal carried by each car, a "passenger's controller" for each of several intermediate floors and each of which is operable from one of said floors and adapted to control the signals of both cars, a part for each car moved correspondingly to the movement of its car and causing the signal of that car to be operative only when one of said controllers has been operated and that car is approaching the floor from which said controller has been operated, devices for each car corresponding to each of said floors for restoring the signals of both cars to normal condition, and a "starter's controller" for each car operable from the "starting" floor and either of which, when operated, makes the signal of only its car inoperative, and means for automatically restoring said "starter's controller" to normal condition when said car reaches a predetermined point in the shaft. 115

6. In an elevator signaling apparatus in combination, two elevator cars and shafts, an electrically operated visual signal carried by each car, a "passenger's controller" for each of several intermediate floors and each of which is operable from one of said floors and adapted to control the signals of both cars, a part for each car moved correspondingly to the movement of its car and causing the signal of that car to be operative only when one of said

- controllers has been operated and that car is approaching the floor from which said controller has been operated, devices for each car corresponding to each of said floors for restoring the signals of both cars to normal condition and 5 automatically operated by the movement of said cars, and a "starter's controller" for each car operable from the "starting" floor and either of which, when operated, makes the signal of only its car inoperative.
6. In an elevator signaling apparatus in combination, 10 two elevator cars and shafts, an electrically operated visual signal carried by each car, means controlling the circuits to said signals and comprising push button mechanism at each of several intermediate floors and a part for each car moved correspondingly to the movement of its car 15 and causing the signal circuit of that car to be closed only when one of said buttons has been operated and that car is approaching the floor at which said button has been operated, electrically operated restoring mechanism corresponding to each of said floors and adapted to restore the 20 signal circuit of both cars to normal condition, and a "starter's controller" for each car operable from the starting floor and either of which, when operated, opens the signal and restoring circuits of its car only.
7. In an elevator signaling apparatus in combination, 25 two elevator cars and shafts, an electrically operated visual signal carried by each car, means controlling the circuits to said signals and comprising push button mechanism at each of several intermediate floors and a part for each car moved correspondingly to the movement of its car 30 and causing the signal circuit of that car to be closed only when one of said buttons has been operated and that car is approaching the floor at which said button has been operated, electrically operated restoring mechanism corresponding to each of said floors and adapted to restore the 35 signal circuit of both cars to normal condition, a "starter's controller" for each car operable from the starting floor and either of which, when operated, opens the signal and restoring circuits of its car only, and means operated by the movement of that car when at a predetermined point 40 in its travel to automatically close the breaks made in said signaling and restoring circuits by said "starter's controller".
8. In an elevator signaling apparatus in combination, 45 two elevator cars and shafts, electrically-operated visual signaling means carried by each car for signaling the operator, an electric signal lamp for each shaft at each of several floors for signaling intending passengers, means, including a "passenger's controller" operable from each floor and a part for each car moved correspondingly to the 50 movement of its car, adapted to cause a floor lamp to be lighted only when its "passenger's controller" has been operated and its car is approaching the floor from which said controller has been operated, restoring means for each shaft for restoring the signal circuits of both cars to 55 normal condition, and a "starter's controller" for each car operable from the starting floor and either of which, when operated, prevents the operation of the restoring means of that shaft only.
9. In an elevator signaling apparatus in combination, 60 two elevator cars and shafts, electrically-operated visual signaling means carried by each car for signaling the operator, an electric signal lamp for each shaft at each of several floors for signaling intending passengers, means, including a "passenger's controller" operable from each floor and a part for each car moved correspondingly to the 65 movement of its car, adapted to cause one of said floor lamps to be lighted only when its "passenger's controller" has been operated and its car is approaching the floor from which said controller has been operated, means for each shaft for restoring the floor lamp circuits of both 70 cars to normal condition, and a "starter's controller" for each car operable from the starting floor and either of which, when operated, prevents the operation of said floor lamp of only the corresponding car.
10. In an elevator signaling apparatus in combination, 75 two elevator cars and shafts, electrically operated visual signaling means carried by each car for signaling the operator, an electrically-operated signal for each car at each of several floors for signaling intending passengers, means, including a "passenger's controller" operable from each floor and a part for each car moved correspondingly to the 80 movement of its car, adapted to cause a floor signal and a car signal to be operated only when a "passenger's controller" has been operated and a car is approaching the floor from which said controller has been operated, a separate signal carried by each car for signaling the operator, and a "starter's controller" for each car and either of which, when operated, operates the said separate car signal and cuts out the floor and car signals of only the 85 corresponding car.
11. In an elevator signaling apparatus in combination, 90 two elevator cars and shafts, an electrically operated visual signaling device carried by each car to signal the operator, a "passenger's controller" for each of several intermediate floors and each of which is operable from one of said floors and adapted to control the signaling device of both cars, a part of each car moved correspondingly to the movement of its car and causing the signaling device of that car to be operative only when one of said controllers has been operated and that car is approaching 95 the floor from which said controller has been operated, means for restoring said signaling devices to normal condition, and a controller for each car stationarily located at a floor and either of which, when operated, cuts out the signaling device of its car only.

Signed at New York, N. Y., this 28th day of March, 1907.
CHARLES A. REINERS.
